UNITED STATES PATENT OFFICE.

NILS H. ANDERSON, OF MIDDLETOWN, CONNECTICUT, ASSIGNOR TO THE NOISELESS TYPEWRITER COMPANY, OF MIDDLETOWN, CONNECTICUT, A CORPORATION OF CONNECTICUT.

TYPE-WRITING MACHINE.

1,264,590.

Specification of Letters Patent. Patented Apr. 30, 1918.

Application filed October 11, 1913. Serial No. 794,594.

To all whom it may concern:

Be it known that I, NILS H. ANDERSON, a citizen of the United States, residing at Middletown, in the county of Middlesex and 5 State of Connecticut, have invented certain new and useful Improvements in Type-Writing Machines, of which the following is a full, clear, and exact description, such as will enable others skilled in the art to which 10 it appertains to make and use the same.

This invention relates to typewriting machines, and with regard to certain more specific features thereof, to universal bar mechanism and associated and coacting parts for 15 controlling the step-by-step or letter-spacing movement of the carriage.

One of the objects of the present invention is to provide a simple and practical universal bar mechanism characterized by 20 its lightness and ease of movement, yet possessing strength and rigidity. Another object is to provide a universal bar mechanism which will be efficient in use and operation and inexpensive to manufacture and 25 install. A further object is to provide a universal bar mechanism which will be substantially noiseless in its operation, and provided with various adjustments to obtain the desired touch and timing between the 30 type action and the escapement mechanism for permitting rapid and accurate operations. Other objects will be in part obvious and in part pointed out hereinafter.

The invention accordingly consists in the 35 features of construction, combinations of elements and arrangement of parts which will be exemplified in the construction hereinafter set forth, and the scope of the application of which will be indicated in the following claims.

In the accompanying drawings, wherein is shown one of the various possible embodiments of the invention,—

Figure 1 is an elevational view showing 45 such parts of a typewriting machine as are necessary to understand one embodiment or application of the present invention thereto;

Figs. 2 and 3 are detail views of the universal bar mechanism in an intermediate

and the final position, respectively, assumed during the printing operation; and

Fig. 4 is a plan view, partly in section, showing the manner of supporting the universal bar.

55

Similar reference characters refer to similar parts throughout the various views of the drawings.

Conducive to a clearer understanding of the present invention, there is illustrated in Fig. 1 such portions of a complete type action as are necessary to understand the relationship between the type action and the universal bar mechanism. This type action, which forms the subject-matter of 60 a separate application filed by me August 6, 1913, Serial No. 783,331, forms no part of the present invention except in so far as certain features thereof may enter into certain combinations hereinafter set forth in 65 the claims. This type action comprises in brief a straight-thrust type carrier 1 adapted to coact with a flat platen 2 adjacent the platen roller 3. The type carrier is moved from a key 4 mounted adjacent the keyboard 70 of the machine and connected with the type carrier 1 through a key lever 5 provided with a vertically disposed pull wire 6 connected at its opposite end to a pivotally mounted lever 7 adapted to have a rocking 75 or heel and toe action upon one arm of a bell crank lever 8. This bell crank lever, which is of the duplex type, is provided with an upwardly extending arm 9 between the parts of which is pivoted a momentum 80 accumulator lever 10 carrying a weight 11 at one end and having its opposite end 12 pivotally connected to a lateral projection of a duplex link 13. One end 14 of the link 13 is pivotally mounted upon an adjustable 85 bracket 15 which may be moved toward and from the printing point under the action of an adjusting screw 16. The opposite end 17 of the link 13 is pivotally connected with a duplex link 18 straddling the type carrier 90 1, and pivoted at 19 to a central portion thereof.

It will thus be seen that as the key 4 is depressed the pull wire 6 will be moved downward causing the lever 7 to rock upon 100

the arm 8 of the bell crank lever. This will cause the upper end of the arm 9 to swing rearward, and the acquired momentum of the movable weight will straighten the 5 toggle formed by the links 13 and 18, thereby positively moving the type silently into contact with the platen, and exerting a compressive or squeezing action thereon in contradistinction to the usual impact or 10 blow characteristic of most forms of typewriting machines. As the toggle formed by the levers 13 and 18 assumes extended position, a reverse toggle will be formed by the arm 9 of the bell crank lever and the right-hand portion of the accumulator lever 10.

At the same time the parts move into printing position under normal operation, the accumulator lever 10 having acquired the momentum as above stated also carries 20 the levers 7 and 8 out of contact after an arm 20 of the key lever 5 has engaged a silencing stop 21. The spring 22 intermediate the arm 8 and the upper part of the bracket 15 will immediately tend to bring 25 the levers 7 and 8 back into contact regardless of subsequent movement or release of the key lever 5. As the key 4 is released, however, the spring 22, as well as the spring 23 connected with the rear end of the key 30 lever will complete the return movement of the parts to normal position. A pad 24 is designed to arrest silently the return movement of the momentum accumulator weight while a pad 25 supported from vertically 35 adjustable studs 26 (only one being shown) coacts with a projection 27 of the bell crank lever for silently arresting its actuating movement.

It is believed from the above description 40 that the general construction and operation of the type action as a whole is clear, and a further more detailed statement thereof is unnecessary.

Instead of positioning the universal bar 45 mechanism beneath the key levers, as is done in many forms of typewriting machines, it is, in the present case, directly associated with certain movable parts of the type action, in order to obtain a more rapid and 50 accurate operation of the escapement mechanism, regardless of the character of the touch in actual operation exerted upon the actuating keys. It is, therefore, found to be advisable to position the universal bar 30 55 in the upper front part of the machine directly beneath a saddle 31 carried by the rearwardly extending arm 8 of the bell crank lever of each action. As is well known to those familiar with the Noiseless typewriting 60 machine, to which the present invention is especially applicable, the type are radially arranged with respect to a common printing point. The bell crank levers are therefore correspondingly arranged, and in order that 65 the universal bar may have the same rela-

tive position to all of them it is curved, as shown more clearly in Fig. 4. This universal bar, which is curved or U-shaped, comprises a sheet metal framework provided with three rearwardly extending ears 32, one 70 near each end and one in the middle. To these ears are pivotally connected supporting arms 33 all of the same length, each pivotally mounted at their opposite ends on forwardly and rearwardly adjustable brackets 75 34 having slotted portions 35 through which bolts or screws 36 pass into the tapped-out studs 37 supported from any convenient part of the frame of the machine. These studs, only one of which is shown in Fig. 80 1, are similar to the stud 26 immediately thereabove supporting the silencer pad 25. The arms 33 being of the same length or effective swinging radius tend to insure an equal vertical movement of all portions of 85 the universal bar.

Projecting downward from each end of the universal bar is a leg 38 and from the central part, a diagonally disposed and rearwardly extending leg 40. The lower ends 90 of these legs 38 and 40 are pivotally connected by means of pivoted screws, or the like, to the rear end of levers 41, the opposite ends of which are secured by means of straps 42 to a universal rock shaft 43 pivotally mounted in adjustable trunnions 44 at the ends thereof, the trunnions being supported from any convenient part of the frame of the machine and held in place by check nuts 45. Extending downward from the central or middle part of the universal rock shaft is an arm 46 forming, with the arms 41, a bell crank lever. The lower end 95 of the arm 46 is pivotally connected in any desired manner with a sheet metal connecting rod 47. This connecting rod is provided with a threaded sheet metal connection 48 at its rear end to a pull wire 50 extending rearwardly to an escapement rocker 51 carrying escapement mechanism coacting with the escapement wheel or rack 52. This escapement rack is, of course, connected with the platen carriage in the usual and well known manner to accomplish a letter-spacing 100 movement thereof.

The connecting rod 47 is provided, at its front end, with a self-locking adjusting nut 53 carrying a pad 54 adapted to engage the front side of a comb member 55 for guiding the up and down movement of the key levers. This adjustable lock nut and pad are adapted to arrest silently the rearward movement 110 of the connecting rod 47 as the parts return to normal position after each depression of a key lever, or as when moving from position 115 shown in Fig. 3 to that shown in Fig. 1. By moving this nut 53 the initial position of the universal bar and its relation to the type actions is controlled. In practice, it is 120 found desirable that the engagement of the 125 130

universal bar by the fork 31 carried between the duplex portions of the lever 8 should be slightly previous to the arrival of the type at the printing position, or just previous to the time that the key lever is arrested in its downward movement by the pad 21 and before the levers 7 and 8 move out of contact. The object of this is to assure that the downward movement of the universal bar shall be started by the energy of the operator's finger rather than depend entirely upon the momentum obtained by the momentum accumulator. This feature is, however, optional and in some classes of operation it may be desirable not to start the universal bar until the key lever has been brought to rest. It is sufficient to state that satisfactory universal bar movements can be secured in this manner, but possibly at less speed. The self-locking adjusting nut 53 can be manipulated by hand, and requires the use of no special tools, so that the mechanism may be changed from one adjustment to another at a moment's notice, as desired.

At the opposite end of the connecting rod 47 is positioned a second adjusting nut 56 similar in size and construction to the nut 53. This nut forms one abutment for a return spring 57, the opposite end of which bears against a collar 58 adjacent a transverse supporting member 60 through which the connecting rod 47 passes. This spring acts not only to return the universal bar to normal upward position, but also to return the escapement rocker to normal position and to assist, through the universal bar, in the return of the type actions to normal position. The tension of this spring is adjusted by the lock nut 56, without, however, in any way affecting the timing of the escapement mechanism.

The escapement mechanism herein used is preferably that type known as "reverse" escapement, that is, an escapement in which the carriage stands normally at rest with the teeth of the escapement wheel bearing against the fixed dog instead of the movable dog carried by the escapement rocker. By using a reverse escapement it is necessary, due to its rapidity of movement, that the timing between the type action and the escapement through the universal bar should be extremely accurate and the universal bar movement very rapid, in order to avoid either double printing or double spacing. In actual practice, in rapid operation the movable dog does not have a sufficient interval of time to engage the escapement wheel, the escapement wheel engaging only the fixed dog, which passes rapidly out of the path of travel of one tooth and back to normal position for engagement with the next tooth of the escapement wheel, all of which necessitates exceedingly rapid and very accurate universal bar mechanism.

In order to change the timing of the escapement, it is necessary to provide for an adjustment in the working length of the escapement connection from the pivot of the escapement rocker. This is provided by the adjustment of the pull wire 50 which is provided at its ends with right and left threads engaging a tapped-out sleeve portion in the end of the connecting rod 47 and a socket carried by the escapement 75 rocker.

The operation of this device is substantially as follows: As any key lever 5, for example, is depressed to move the type carrier rearward into printing position, 80 the lever 7 rocks upon the lever 8 to carry the yoke or fork 31 into engagement with the upper edge of the universal bar 30, and when the key lever is arrested by engagement between the stop 20 and pad 21 the 85 universal bar will have been only very slightly actuated or moved to the position shown in Fig. 2, in which position it will be noted that the pivot point between arm 46 and rod 47 is moved slightly toward the 90 left. This movement is not sufficient under ordinary circumstances and adjustment to actuate the escapement mechanism, but merely to move it into a position where it will be instantly released as the type carrier 95 completes its printing operation. The type during this operation moves from a position closely adjacent the platen into contact therewith under the action of the momentum accumulator 11, as fully set forth in the above 100 referred to application, and instantly returns to the position clear of the platen and other actions regardless of subsequent operations or releasing of the key. It is this movement from the position shown in Fig. 105 2 to that shown in Fig. 3 and back again to that shown in Fig. 2 that completes the printing operation and steps the carriage through the escapement mechanism. In normal operation, of course, the key would be 110 released immediately and another key depressed probably before the first key reached a position of rest. In fact, it is unnecessary for the keys to return to normal position to effectively print and also space the carriage, 115 as both operations take place only during the final movement of the type.

A construction of this kind is particularly advantageous and important in the ease with which a so-called "dead" key action may be 120 used, that is, an action the operation of which is without subsequent universal bar movement. It is necessary or desirable sometimes, in printing certain characters in foreign languages, to apply different accent marks over 125 the same letter in different words. To accomplish this result all that is necessary is to remove from a type action devoted to accent marks the yoke or fork straddling the universal bar and the operation of that type 130

action will then be unaccompanied by universal bar and escapement movement.

From the above description it will be seen that the present invention embodies a simple and practical universal bar mechanism permitting rapid and efficient operation of the machine, and is fully designed to accomplish, among others, all of the objects and advantages above set forth.

10 As many changes could be made in the above construction and many apparently widely different embodiments of this invention could be made without departing from the scope thereof, it is intended that all 15 matter contained in the above description or shown in the accompanying drawings shall be interpreted as illustrative and not in a limiting sense.

Having described my invention, what I 20 claim as new and desire to secure by Letters Patent is:

1. In a typewriting machine, in combination, a curved substantially vertically movable universal bar, a rock shaft, an escapement member, and connections between said bar and said shaft and between said shaft and said escapement member.

2. In a typewriting machine, in combination, a curved substantially vertically movable universal bar, a rock shaft, an escapement member, and connections between said bar and said shaft and between said shaft and said escapement member comprising a plurality of links and an adjustable rod.

3. In a typewriting machine, in combination, a universal bar curved about a vertical axis, an escapement dog, means adapted to support said bar and permit movement thereof in a predetermined direction, a member adapted to operate said escapement dog and mounted to move transversely to said movement of the universal bar, and means whereby the movement of said bar causes movement of said member.

4. In a typewriting machine, in combination, a universal bar having downwardly extending legs, an escapement dog, means adapted to support said bar and permit movement thereof in a predetermined direction, a member adapted to operate said escapement dog and mounted to move transversely to said movement of the universal bar, and means whereby the movement of said bar causes movement of said member.

5. In a typewriting machine, in combination, a curved universal bar at the front of the machine, an escapement dog in the rear of said universal bar, means adapted to support said bar pivotally and permit movement thereof in a vertical direction, a member adapted to operate said escapement dog and mounted to move transversely to said movement of the universal bar, and means whereby the movement of said bar causes movement of said member.

6. In a typewriting machine, in combination, a universal bar curved about a vertical axis, an escapement dog, means adapted to support said bar and permit movement thereof in a predetermined direction, a member adapted to operate said escapement dog and mounted to move transversely to said movement of the universal bar, a spring urging said member in one direction, and means whereby the movement of said bar causes movement of said member.

7. In a typewriting machine, in combination, a curved universal bar, an escapement dog, means adapted to support said bar pivotally and permit movement thereof in a predetermined direction, a member adapted to operate said escapement dog and mounted to move transversely to said movement of the universal bar, a spring urging said member in one direction, and means whereby the movement of said bar causes movement of said member.

8. In a typewriting machine, in combination, a universal bar, an escapement dog, means adapted to support said bar and permit movement thereof in a predetermined direction, a member adapted to operate said escapement dog and mounted to move transversely to said movement of the universal bar, a spring surrounding said member having portions bearing respectively against said member and the frame of the machine to urge the member in the direction of its length, and means whereby the movement of said bar causes movement of said member.

9. In a typewriting machine, in combination, a curved universal bar, an escapement dog, means adapted to support said bar pivotally and permit movement thereof in a predetermined direction, a member adapted to operate said escapement dog and mounted to move transversely to said movement of the universal bar, a spring surrounding said member having portions bearing respectively against said member and the frame of the machine to urge the member in the direction of its length, and means whereby the movement of said bar causes movement of said member.

10. In a typewriting machine, in combination, a universal bar curved about a vertical axis, an escapement dog, means adapted to support said bar and permit movement thereof in a predetermined direction, a member adapted to operate said escapement dog and mounted to move transversely to said movement of the universal bar, and means comprising a rock shaft and connections between said bar and said member whereby the movement of said bar causes movement of said member.

11. In a typewriting machine, in combination, a curved universal bar, an escapement dog, means adapted to support said bar and permit movement thereof in a ver-

tical direction, a member adapted to operate said escapement dog and mounted to move transversely to said movement of the universal bar, and means comprising a rock 5 shaft and connections between said bar and said member whereby the movement of said bar causes movement of said member.

12. In a typewriting machine, in combination, a curved universal bar having an 10 escapement dog, means adapted to support said bar pivotally and permit movement thereof in a predetermined direction, a member adapted to operate said escapement dog and mounted to move transversely to said 15 movement of the universal bar, a spring surrounding said member having portions bearing respectively against said member and the frame of the machine to urge the member in the direction of its length, and 20 means whereby the movement of said bar causes movement of said member.

13. In a typewriting machine, in combination, a curved universal bar, an escapement dog, means adapted to support said bar and permit movement thereof in a predetermined direction, a member adapted to operate said escapement dog and mounted to move transversely to said movement of the universal bar, means whereby said bar 25 may be adjusted in the direction of its movement, and means whereby the movement of said bar causes movement of said member.

14. In a typewriting machine, in combination, a curved universal bar, an escapement dog, means adapted to support said bar and permit movement thereof in a predetermined direction, a member adapted to operate said escapement dog and mounted to move transversely to said movement of the universal bar, means whereby said member 30 may be adjusted to vary the position of said escapement dog, and means whereby the movement of said bar causes movement of said member.

15. In a typewriting machine, in combination, a curved universal bar, an escapement dog, means adapted to support said bar and permit movement thereof in a predetermined direction, a member adapted to operate said escapement dog and mounted to move transversely to said movement of the universal bar, means whereby said bar and said dog 50 may be adjusted conjointly, and means whereby the movement of said bar causes movement of said member.

16. In a typewriting machine, in combination, a curved universal bar, an escapement dog, means adapted to support said bar and permit movement thereof in a predetermined direction, a member adapted to operate said escapement dog and mounted to move transversely to said movement of the universal bar, means whereby said member 55 may be adjusted independently of said universal bar to vary the position of said es-

capement dog, and means whereby the movement of said bar causes movement of said member.

17. In a typewriting machine, in combination, a universal bar curved about a vertical axis, an escapement dog, means adapted to support said bar and permit movement thereof in a predetermined direction, a member adapted to operate said escapement dog and mounted to move transversely to said 70 movement of the universal bar, a spring urging said member in one direction, means whereby the tension of said spring may be adjusted, and means whereby the movement of said bar causes movement of said member. 80

18. In a typewriting machine, in combination, a universal bar curved about a vertical axis, an escapement dog, means adapted to support said bar and permit movement thereof in a predetermined direction, a member adapted to operate said escapement dog and mounted to move transversely to said movement of the universal bar, a spring urging said member in one direction, means whereby the tension of said spring may be 85 adjusted and locked automatically in adjusted position, and means whereby the movement of said bar causes movement of said member.

19. In a typewriting machine, in combination, a universal bar curved about a vertical axis, an escapement dog, means adapted to support said bar and permit movement thereof in a predetermined direction, a member adapted to operate said escapement dog and 95 mounted to move transversely to said movement of the universal bar, a spring urging said member in one direction, means whereby the tension of said spring may be adjusted, means independent of said last means 100 whereby the universal bar may be adjusted in its direction of movement, and means whereby the movement of said bar causes movement of said member.

20. In a typewriting machine, in combination, a universal bar curved about a vertical axis, an escapement dog, means adapted to support said bar and permit movement thereof in a predetermined direction, a member adapted to operate said escapement dog and mounted to move transversely to said movement of the universal bar, a spring urging said member in one direction, means whereby the tension of said spring may be 110 adjusted and locked automatically 115 in adjusted position, means independent of said last means whereby the universal bar may be adjusted in its direction of movement, and means whereby the movement of said bar causes movement of said member. 120

21. In a typewriting machine, in combination, a U-shaped universal bar, and two sets of levers for controlling the movement of said universal bar.

22. In a typewriting machine, in com- 130

bination, a universal bar, a set of levers supporting said bar for insuring a vertical movement of all parts thereof, and a second set of levers substantially parallel to said 5 first set of levers with a position therebelow for assuring parallel movement.

23. In a typewriting machine, in combination, a universal bar, a set of levers supporting said bar for insuring a vertical 10 movement of all parts thereof, a second set of levers substantially parallel to said first set of levers with a position therebelow for assuring parallel movement, an escapement mechanism, and connections between 15 the said escapement mechanism and said set of levers.

24. In a typewriting machine, in combination, a curved universal bar, parallel arms connected to different points of said 20 universal bar having the same swinging radius whereby the universal bar moves in a substantially vertical direction, and a set of levers pivotally connected with the lower part of said universal bar.

25. In a typewriting machine, in combination, a rock shaft, an escapement mechanism, an operative connection between said parts, including a rod horizontally positioned adjacent the bottom of the machine, 25 and means associated with said rod and accessible from beneath the machine for adjusting the normal position thereof.

26. In a typewriting machine, in combination, a universal bar, a type action, 30 including a member to actuate said bar, an escapement mechanism, an operative con-

nection between said bar and said mechanism, means associated with said connection to adjust the normal relative positions thereof, and means associated with said bar 40 to adjust the position thereof with respect to its operating member.

27. In a typewriting machine, in combination, a universal bar, a rock shaft connected therewith, an escapement mechanism, 45 connections between the rockshaft and the universal bar, connections including a longitudinally movable member between said escapement mechanism and said rock shaft, and a coil spring positioned about said 50 member between the escapement mechanism and rock shaft.

28. In a typewriting machine, in combination, a universal bar, a rock shaft connected therewith, an escapement mechanism, 55 connections between the rock shaft and the universal bar, connections including a longitudinally movable member between said escapement mechanism and said rock shaft, a coil spring positioned about said member 60 between the escapement mechanism and rock shaft, and means for adjusting the tension of said spring comprising an adjusting nut movable in the direction of the length of the part on which it is mounted. 65

In testimony whereof I affix my signature, in the presence of two witnesses.

NILS H. ANDERSON.
